UNITED STATES PATENT OFFICE.

ROBERT E. GODFREY, OF NEW YORK, N. Y.

DESIGN FOR A TEXTILE FABRIC.

50,888.

Specification for Design.

Patented June 5, 1917.

Application filed April 2, 1917. Serial No. 159,339. Term of patent 3½ years.

To all whom it may concern:

Be it known that I, ROBERT E. GODFREY, a citizen of the United States of America, residing at New York city, county and State of New York, have invented a new, original, and ornamental Design for a Textile Fabric, of which the following is a specification, reference being had to the accompanying drawing, forming part hereof, which represents a face view of a piece of fabric embodying my new design.

I claim:

The ornamental design for a textile fabric as shown.

Signed at New York city, New York, this 27th day of March, 1917.

ROBERT E. GODFREY.

Witnesses:

MARK KAHN,
AARON H. MARX.
